UNITED STATES PATENT OFFICE.

EDWIN C. BALLMAN, OF ST. LOUIS, MISSOURI.

SHORT-CIRCUITING DEVICE.

Application filed September 4, 1925. Serial No. 54,456.

This invention pertains to electric motors and more particularly to a device for short circuiting the commutator as is done in the starting operation of many types of commu-
5 tator motors.

The customary manner of short circuiting a commutator involves the use of a series of contactors, usually operated by centrifugal force, and arranged to contact with the com-
10 mutator segments at a predetermined motor speed. These contactors connect the various commutator segments with a short circuiting ring. At the instant at which the commutator is short circuited there is usually a
15 heavy rush of current through the contactors. This current must pass through the point of contact between the contactor and the commutator segment. The usual ex-
perience has been that considerable arcing
20 takes place at these points of contact. After numerous operations the effect of such arcing is to cause the commutator segments and the contactors to become rough, so that a good contact is no longer possible. Accordingly
25 the effectiveness of the short circuit is im-
paired when such roughening or corrosion of the contact points takes place.

One of the objects of this invention, there-
30 fore, is to provide a short circuiting device
of novel construction which will obviate the trouble due to corrosion of the contact points.

Another object is to provide an auxiliary set of contactors which will accomplish the make and break operations so that the main
35 contactors will be relieved of the arcing.

Another object is to provide such a device which will be simple and economical to man-
ufacture and reliable in service.

Further objects will appear from the fol-
40 lowing description taken in connection with the accompanying drawing in which:

Figure 1 is a view partly in section of a commutator equipped with a short circuiting device embodying this invention;

Figure 2 is a partial end view of Figure 1;
45 and

Figures 3 and 4 are detail views illustrating the action of the contactors.

Referring to the accompanying drawing 1
50 designates the motor shaft which may have mounted thereon in any suitable manner a commutator hub 2, carrying commutator segments 3. This may be of any ordinary construction well known in the art. Mount-
55 ed on the shaft 1 just in front of the commutator is a metallic cup 4. This should be

made of a material having high electrical conductivity such as brass or copper. The cup 4 is adapted not only to provide a mounting for the short circuiting contactors as will 60 presently be described, but also acts as a short circuit ring to carry the inter-change of currents between said contactors.

Pivoted in the ring 4 are two series of contactors, a series of main contactors 5 and a 65 series of auxiliary contactors 6. These contactors are formed by punching, or other suitable operation, of wedge shaped copper or brass similar to that used for commutator segments. The contactors have the form 70 shown in Figures 1, 3 and 4 comprising a lever portion 7, a tail piece 8, a sharply angled point 9, slightly rounded to form a pivot, a weight or body portion 10 and contacting faces 11 and 12. As will be seen from 75 Figure 3 the main and auxiliary contactors are identical in form except for the contacting portions, that of the auxiliary contacts 6 being longer than that of the main contacts 5 so that the contacting face 12 of 80 each auxiliary contactor will extend beyond the contacting faces 11 of the main contactors. Such construction provides that the auxiliary contactors will make contact in ad-
85 vance of and break contact after the main contactors.

The contactors are mounted in the ring 4 in such a way that the pivots 9 of the contactors fit into the corner at the bottom of the rim 13 of said ring. The contactors 90 are assembled close together all around the cup 4 as shown in Figure 2, there being approximately three main to one auxiliary contactor. This mounting provides that each contactor will have a pivot at its corner 9 95 in the cup 4. A pressure plate 14 of circular form and fitting over the shaft 1 so as to slide therealong engages the tail pieces of all of the contactors and is pressed thereagainst by a coil spring 15 surrounding the 100 shaft 1. This plate operates to press the contactors into the cup 4, so that their tail pieces 8 will all be forced down against the rim of the cup so as to maintain their contact faces clear of the commutator as shown 105 in Figure 3.

The assembled contactors are protected by a cup shaped cover 16 mounted on the shaft 1 and having a flange 17 extending over the contactors and toward the commutator. The cover 16 is retained in place by a pair of half ring sections 18 fitting into an annular

groove 19 in the shaft 1 and each is provided with an inwardly projecting ear 20 extending through a notch 21 in the cover 16. The spring 15 bears at one end against the interior of the cover 16 and at its other end against the pressure plate 14 so that this spring not only provides pressure for retracting the contactors from engagement with the commutator but also serves to retain the cover 16 in locking engagement with the sections 18, which not only hold the cover 16 in place but are themselves retained in place thereby.

In the operation of this device, when the motor is at rest, the contactors assume the positions illustrated in Figure 3. When the motor is started and attains a predetermined speed the centrifugal force of the body portions 10 of the contactors, acting through the lever portions 7 and the tail pieces 8 overcomes the pressure of the plate 14. When this takes place the contactors turn on the pivots 9 so as to bring the contacting faces 12 and 11 into engagement with the commutator segments 3. The auxiliary contactors make contact first at their faces 12 and the arcing takes place at these contacts. Subsequently as the motor speed increases further, the main contacts engage the commutator segments at their faces 11. When this point has been reached the contactors are in the positions illustrated in Figure 1. Here both series of contactors are in engagement with the commutator. However, the tail pieces 8 of the main contactors have pushed the pressure plate 14 outwardly so as to free the tail pieces of the auxiliary contactors 6 as illustrated in Figure 1. The further action of centrifugal force on the auxiliary contactor will now move them in such a way that the pivot point 9 slides outwardly along the rim 13 until the tail pieces again engage the plate 14. This position is shown in Figure 4. During this movement the auxiliary contactors have a slight rocking motion at their contact faces 12 so that a varying contact is obtained at this point which assists in reducing the corrosion due to arcing. It will further be noted that the contact faces 11 and 12 are displaced radially with respect to one another. Accordingly they will engage the commutator at different parts thereon. This provides that the arcing at the face 12 will occur at a different point on the commutator than that engaged by the faces 11.

It will be seen, therefore, that in accordance with this invention a short circuiting device is provided in which the arcing is confined to a series of auxiliary contactors and to a certain place on the commutator segments, while the main short circuiting operation is accomplished by the main contactors which touch the commutator at a

point which is not engaged by the auxiliary contactors and which is, therefore, kept clean and uncorroded by arcing. The auxiliary contacts engage the segments with a slight rolling or slipping engagement so that the roughness produced by arcing will be correspondingly reduced. As the contactors are not confined circumferentially nor limited to any fixed position, the continued operation of this device will shift the contactors circumferentially with respect to the commutator so that the corrosion due to arcing will be distributed over the entire circumference of the commutator and not confined to any one point.

The device is very cheap to manufacture. A contactor may be formed by punching from suitable metal. The cup 4, the plate 14, the cover 16 and the sections 18 may each be made of suitable sheet metal formed at a single machine operation, and therefore, very cheap. The spring 15 is subject to only slight movement upon operation of the contactors and, therefore, its change in strength due to compression will be slight while the contactors move radially outwardly, thereby increasing the force which they exert upon the spring. Accordingly the contactors will move positively against the spring tension, an action which is desirable in order to avoid excessive arcing. The cover 16 provides protection for the device while at the same time affording easy access thereto.

This construction also provides for easy accessibility, as the device is easily disassembled by simply pushing in the cover 16 to free the sections 18 which are then removed and the cover slipped back on the shaft. This releases the spring 15 and the plate 14 so as to render all the contactors accessible for removal or replacement. The contactors are thus easily removable for cleaning the contacting surface of the commutator.

It is obvious that various changes may be made in the details of construction without departing from the spirit of this invention; it is to be understood, therefore, that this invention is not to be limited to the specific details shown and described.

Having thus described the invention what is claimed is:

1. In an electric motor, a short-circuiting device, comprising, a commutator, a series of main contactors adapted to make contact with the commutator segments, and a series of auxiliary contactors adapted to make contact with the commutator segments in advance of said main contactors.

2. In an electric motor, a short-circuiting device, comprising, a commutator having segments, a series of main contactors centrifugally operated to contact with said segments at a predetermined motor speed and a series of auxiliary contactors centrifugally

- operated to contact with said segments in advance of said main contactors.
3. In an electric motor, a short-circuiting device, comprising, a commutator having segments, a series of main contactors centrifugally operated to contact with said segments at a predetermined motor speed and a series of auxiliary contactors centrifugally operated to contact with said segments at a different place on the commutator from said main contacts.
4. In an electric motor, a short-circuiting device comprising, a commutator having segments, a series of main contactors and a series of auxiliary contactors centrifugally operated to contact with said segments at a predetermined motor speed, said main and auxiliary contactors having their contacting portions relatively displaced.
5. In an electric motor, a short circuiting device, comprising, a commutator having segments, a series of main contactors centrifugally operated to contact with said segments at a predetermined motor speed and a series of auxiliary contactors centrifugally operated to contact with said segments and to disengage said segments after said main contactors.
6. In an electric motor, a short-circuiting device, comprising, a commutator having segments, a series of main contactors cen-
- trifugally operated to contact with said segments at a predetermined motor speed and a series of auxiliary contactors centrifugally operated to contact with said segments in advance of said main contactors and with a varying contact.
7. In an electric motor, a short-circuiting device, comprising a commutator having segments, a series of main contactors and a series of auxiliary contactors centrifugally operated to contact with said segments at a predetermined motor speed, a cover for said contactors, locking means for retaining said cover in place, said locking means being adapted to be retained by said cover, and resilient means for retaining said cover in engagement with said locking means.
8. In an electric motor, a short-circuiting device, comprising, a commutator having segments, a series of main contactors and a series of auxiliary contactors centrifugally operated to contact with said segments at a predetermined motor speed, a spring for restraining said contactors against the centrifugal force thereof, a cover for said contactors, and a loose locking element adapted to retain said cover and to be retained by said spring.

In testimony whereof I affix my signature this 21st day of April 1925.

EDWIN C. BALLMAN.
